UNITED STATES PATENT OFFICE.

HENRY HESS, OF WAWA, PENNSYLVANIA.

MULTIGRAPHIC APPARATUS.

1,149,261.

Specification of Letters Patent. Patented Aug. 10, 1915.

Application filed June 12, 1908. Serial No. 438,152.

To all whom it may concern:

Be it known that I, HENRY HESS, a citizen of the United States, residing at Wawa, in the county of Delaware and State of Pennsylvania, have invented certain new and useful Improvements in Multigraphic Apparatus, of which the following is a specification, reference being had therein to the accompanying drawing.

10 My invention relates to multigraphic or other duplicating apparatus and more particularly to that class thereof designed to produce a considerable number of facsimile prints as ordinarily employed for circular or general purposes. Customarily, in the use of such apparatus the body or main portion of the letter is first made and the individual part subsequently added. This 15 ordinarily consists of the address, but in many instances blanks are also left to be filled in with dates, numbers, or other specific data. Such additions are usually made with an ordinary typewriting machine, but it is often difficult to obtain therefrom the effect of 20 uniformity which is regarded as desirable and moreover the second operation involves not only this objection but also expense and loss of time.

It is the purpose of my invention to obviate 25 these difficulties and to permit the writing of the additional data, such as the address, etc., at the same time with the body of the letter.

To this end it consists broadly in the provision 30 of two distinct impression mechanisms arranged to print concurrently upon the same sheet. These impression mechanisms are suitably connected so that one is intermittently actuated during the operation 35 of the other. Thus while the main device is completely actuated so as to print from its entire impression surface, the other or auxiliary device is operated only partially so as to print from a selected portion of its 40 impression surface.

It will be obvious that my invention may 45 be applied in many different forms without departing from its spirit. For the purposes of illustration merely I have shown it as embodied in a well known type of multigraphic apparatus now in commercial use, but it is not my intention thereby to limit its broader and more general application.

Referring to the drawings: Figure 1 is a plan view, partly broken away, of multigraphic apparatus with my invention applied thereto; Fig. 2 is a vertical sectional view thereof taken substantially on the line 2-2 in Fig. 1; and Fig. 3 is a sectional detail view.

The frame or support A may be of any desired or approved construction. Suitably mounted therein is the shaft M carrying the main impression device or cylinder E which is operated by the handle or crank arm m^1 55 attached to the shaft M. The drum or cylinder E is provided with longitudinal grooves or channels e, e , (see Fig. 3), which receive and hold the type c, c . When the type for the body of the letter have been 60 composed or set-up in the channels, the ribbon E^1 , carried by the spools e^1, e^1 , is wound about the periphery of the drum and over the faces of the type. The sheet to be 65 printed is then placed in position, and as the drum is given a complete rotation by the handle m^1 , it is carried between the type and ribbon thereon and the platen or cylinder K and printed in the ordinary manner. The apparatus is also provided with a supply 70 drum B mounted upon a shaft B^1 . This drum B has the grooves or channels b, b , and constitutes the magazine or storage element 75 wherein the type c, c , are normally contained. The drum is capable of rotation about the shaft B^1 to bring it into proper 80 relation with the channels of drum E so that the type may be composed or distributed in the ordinary manner.

All of the parts thus far specifically described 85 are old in the art and constitute no part of my invention.

I have shown my auxiliary printing mechanism, such as would be employed for additional data, addresses, and the like, in the form 90 of a drum G, located at the rear of drum E, and provided with similar channels g, g , spools e^2, e^2 , and ribbon E^2 , and a similar platen K^1 . The drum G is mounted upon 95 and operated by the shaft H which is located upon the frame A in any suitable manner, as by the bracket H^1 . As a considerable 100 number of addresses or similar data can be placed upon the periphery of drum G, it is obvious that it need be operated only for 105 a portion of its circumference at each com-

plete actuation of drum E. This intermittent action is secured through the connections now to be described.

Fast to shaft M is the gear m which 5 meshes into gear i^2 upon the short shaft I mounted in bracket I^1 on frame A. Also connected to shaft I is the gear i provided with teeth i^1 throughout only a portion of its periphery and located in position to engage and actuate gear h^1 on shaft H. It 10 will thus be seen that at each complete rotation of drum E, through the connections described a partial or fractional rotation will be imparted to shaft H and drum G; 15 and that the sheet printed by drum E will further pass through and between the drum G and the platen K ^{1} , thereby adding the address or other data thereto; and that in this manner the letter or similar matter is completed by a single operation of the apparatus. 20

In order to permit of the ready assemblage or distribution of the type in connection with drum G, I have arranged the supply drum B so that it may be brought into proper relation therewith. This I accomplish by mounting the shaft B ^{1} in the frame D which is radially movable about the supporting pivot D ^{2} . In Fig. 1 the drum B is 25 shown by full lines in operative relation to the drum E; but by the pivotal mounting described it may be thrown over until the frame D abuts against and is stopped by the portion a of the frame A, and the drum 30 B and shaft B ^{1} occupy their dotted-line positions, when the drum B will be in similar operative relation to the drum G. To secure the parts firmly in these two positions I locate upon the frame A a spring-pressed 35 locking plunger d which engages with properly located notches d^1 , d^2 , formed in the pivotal frame D.

As shown in the drawings, the auxiliary drum G is of considerably less width than 40 the drum E. This dimension will, however, depend entirely on the character of the data to be carried thereby. The drum G is also shown as detachably secured to the shaft H by means of the catch g^2 connected to the 45 hub g^1 of the drum. The catch g^2 is adapted to engage any one of a series of holding notches h , h , formed on the shaft H, and in this manner the drum may be adjusted to any desired position thereon. For instance, 50 as illustrated in Fig. 1, the drum is in its assembling or distributing position. If it be employed to print addresses, it would occupy the dotted-line position therein. And further, the feature of detachability permits 55 the substitution of any number of similar drums containing different addresses or other data, thereby materially increasing the capacity of the apparatus. Other and similar 60 variations will readily suggest themselves. 65 Thus, instead of a drum I may employ a

chain carrying a series of addresses or the like, which chain would be operated in the same manner as the drum G. This and numerous other equivalents I regard as comprised within the scope of my invention. 70

Having thus described my invention, what I claim and desire to secure by Letters Patent of the United States is as follows:

1. In a multigraphic apparatus, the combination of a main printing cylinder to print the bodies of the letter sheets, an auxiliary printing cylinder in proximity thereto and provided with a plurality of printing forms arranged at intervals thereon, said auxiliary cylinder adapted to print on the letter sheets as they pass from the main cylinder, a gear on the main cylinder, a mutilated gear driven thereby, and a pinion on the auxiliary cylinder in mesh with the mutilated gear; whereby the successive rotations of the main cylinder will act to advance the auxiliary cylinder step by step. 75

2. In a multigraphic apparatus for printing letters, the combination of a flat supporting bed to sustain the letter sheets, a main printing cylinder thereon provided with a printing form adapted by its complete rotations to print the bodies of the letters in succession with a blank space left to be filled in and to advance said sheets along the bed, an auxiliary printing cylinder arranged over said bed in position to act on the sheets fed along the same by the main cylinder and provided with a plurality of individual printing forms at intervals thereon and adapted to print additional matter on the letter sheets in the blank space thereon, and suitable connections between the two cylinders, whereby the auxiliary cylinder will be given a fraction of rotation for each 90 complete rotation of the main cylinder so as to present the individual forms in proper printing relation to the blank space on the successive letter sheets from the main cylinder. 95

3. In a multigraphic apparatus, the combination of two distinct impression mechanisms arranged to print concurrently upon the same sheet, together with storing means for the type, which means are adapted to be brought into operative relation with either of the impression mechanisms. 105

4. In a multigraphic apparatus for printing letters on individual sheets, the combination of a flat supporting bed to support the letter sheets, a main printing form adapted to print the main body portion of the letters in succession with a blank space to be filled in and to feed said sheets along the bed, a shiftable auxiliary co-operating printing device arranged over the bed in position to act on the sheets fed by the main cylinder and provided with individual printing forms disposed with relation to the main form to print in the blank space on the letter sheets, 110 115 120 125 130

said auxiliary printing device being in position to act on the letter sheets in succession after they leave the main printing form, and operative connections between the main printing form and auxiliary printing device operating to shift the auxiliary device to position its different printing forms in printing relation to the blank space on the successive sheets as they leave the main

printing form and operating also to actuate 10 the auxiliary device to effect its printing action.

In testimony whereof I have affixed my signature in presence of two witnesses.

HENRY HESS.
